UNITED STATES PATENT OFFICE.

JOHN P. DOLAN, OF HARTFORD, CONNECTICUT, ASSIGNOR OF TWO-THIRDS TO JOSEPH M. MOTTO, OF HARTFORD, CONNECTICUT.

CLAMP.

1,349,331.

Specification of Letters Patent. Patented Aug. 10, 1920.

Application filed August 20, 1919. Serial No. 318,650.

To all whom it may concern:

Be it known that I, JOHN PATRICK DOLAN, a citizen of the United States, residing at Hartford, in the county of Hartford and 5 State of Connecticut, have invented certain new and useful Improvements in Clamps, of which the following is a specification.

My invention relates to improvements in clamps of the form known as steel carpenters' clamps and the object of my improvement is simplicity and economy in construction and convenience and efficiency in use.

In the accompanying drawing:—

Figure 1 is a side view of my improved 15 clamp in use for holding together two blocks of wood.

Fig. 2 is an end elevation of the same.

Fig. 3 is an elevation of the other end.

Fig. 4 is a sectional view on an enlarged 20 scale and in part broken away on the line 4—4 of Fig. 3.

My improved clamp comprises an elongated bar 10 of rectangular cross-section having fixedly secured at one end a bracket 25 11 that operatively supports a clamping screw 12 that operates a clamping contact piece 13 and having slidably engaged with the body portion an adjustable clamping member to be described.

30 The said adjustable clamping member comprises a block 14 that has an opening 15 that is a sliding fit for the bar 10 and that overhangs the bar 10 on one side suitably to support a contact shoe 16 in a position 35 in opposition to the contact piece 13 so as to coöperate therewith in clamping the blocks of wood, as shown at 17, or other parts to be held together.

The shoe 16 comprises a head 18 at the 40 inner end, a neck or stem 19 of appreciable size and of rectangular cross-section extending outwardly from the said head 18, and a reduced stem 20 extending outwardly from the outer end of the said neck 19.

45 A collar 21 is mounted on the extreme outer end of the reduced stem 20 and a coil spring 22 is mounted on the said reduced stem 20 and positioned between the said collar 21 and the block 14.

50 The outer lateral edge 23 of the main stem or neck 19 is of appreciable length and is directed longitudinally, in parallelism with the bar 10.

The inner lateral edge of the main stem

19, on the side opposed to the bar 10, has a 55 portion 24 of appreciable length that is inclined or tapered, suitably to coöperate with a sliding dog or locking piece 25 for clamping the adjustable clamping structure to the bar 10.

The overhanging portion 26 of the block 14 is constructed and arranged for operatively housing the clamping shoe 16 in the following manner:—A longitudinally directed chamber 27, open on the inner side, is 60 a fit for and receives the main stem 19, and has the outer wall 28 perforated to provide an opening 29 that is a fit for the reduced stem 20.

A laterally directed connecting chamber 70 or passage 30 connects the chamber 27 with the opening 15 for the bar 10, and serves as the housing for the dog 25.

The dog 25 is generally rectangular, has a contacting face 31 at the outer lateral end 75 for coöperating with the inclined edge portion 24 of the stem 19 and at the inner end 32 is of suitable form for coöperating with the opposed edge portion of the bar 10, and has parallel sides 34 that are a loose fit between the opposed end walls 33 of the passage 30.

The said opposed end walls 33 may be slightly rounded or V-shape so as to permit of a slight rocking movement of the dog 25 85 in use.

The spring 22 tends to pull the shoe 16 outwardly and thereby effects a positioning of the dog 25 so as to be in contact with the bar 10, and any pressure on the shoe 16 due 90 to the pressure of the clamping screw 12 operates to increase the hold on the bar.

When the parts are in non-clamping position a slight pressure on the reduced stem 20 serves to release the parts so that the adjustable clamping member can be freely moved back and forth along the bar.

I claim as my invention:—

1. A clamp comprising a bar having a screw clamping member at one end and an 100 adjustable clamping member for being positioned at different positions along the said bar, the said adjustable clamping member comprising a body slidably engaged with the said bar, a shoe for contacting with the 105 work that is slidably engaged with the said body, and a dog positioned between the said shoe and bar and housed in the said body,

and the said shoe having an inclined driving face that coöperates with the said dog for driving the dog against the said bar.

2. A clamp as described in claim 1, and 5 the said adjustable clamping member having a spring arranged to hold the parts in locking position relatively to the said bar.

3. In a clamp comprising a bar and a 10 clamping member for being positioned at different positions along the said bar, the said clamping member comprising a body that is slidably mounted on the said bar, a shoe for engaging with the work and having a supporting portion that is slidably en-

gaged with the said body, and being provided with an inclined edge portion, the said body having a cavity in the portion between the said inclined edge portion and the bar, and a wedge dog housed in the said cavity for engaging with the said inclined 15 edge portion on one side and with the bar on the other side, and the parts being constructed and arranged so that the walls of the said cavity serve to position the said dog for effecting a locking of the clamping member to the bar when pressure is applied to the said shoe.

JOHN P. DOLAN.
